DESIGN FOR A WHEELED TOY

Willis T. Guild, Gulfport, Miss.

Application April 20, 1945, Serial No. 119,116

Term of patent 7 years

(Cl. D34—15)

To all whom it may concern:

Be it known that I, Willis T. Guild, a citizen of the United States, residing at Gulfport, in the county of Harrison and State of Mississippi, have invented a new, original, and ornamental Design for a Wheeled Toy, of which the following is a specification, reference being had to the accompanying drawing, forming part thereof.

The figure is a perspective view of a wheeled toy showing my new design.

I claim:

The ornamental design for a wheeled toy, as shown.

WILLIS T. GUILD.
